UNITED STATES PATENT OFFICE

GUSTAV A. MERKT, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS

REGULATION OF HEATING FURNACES

Application filed March 4, 1932. Serial No. 596,777.

The present invention relates in general to the regulation of heating furnaces. More particularly, the invention provides a regulatory system applicable to furnaces wherein resort is had to recirculation of a portion of the combustion products, as disclosed, for example, in my United States Letters Patent No. 1,814,567, dated July 14, 1931.

The present invention contemplates automatic regulation, in a coordinated manner, of the various factors and elements that affect the composition and temperature of the combustible mixture of fuel, air and recirculated combustion products burned in such a furnace. Other and further objects and advantages of the invention will appear from the following detailed description thereof, taken in connection with the accompanying illustrative drawings, in which—

Figs. 1 and 2 are schematic sectional views illustrating different applications of the principles of my invention to a simple non-regenerative type of heating furnace.

Like reference characters refer to like parts in the different figures.

Referring first to Fig. 1, I have shown in vertical section a heating furnace 1 of simple conventional form, said furnace providing the usual elongated combustion chamber 2, having at one end a fuel port 3 and at the opposite end an exit port 4, through which the products of combustion, after travelling the length of the chamber 2, are discharged into a suitable offtake flue or passage 5. In order to secure a recirculation of a portion of such combustion products through the furnace, an arrangement of drafting apparatus, similar to that employed in my aforesaid Patent No. 1,814,567, may be utilized; to this end, the offtake flue or passage 5 is suitably connected, as by a passage 5', with an outwardly opening Venturi tube or duct 6, within which, in proper relation to the throat thereof, is disposed an upwardly directed nozzle 7, the latter being supplied with air by an exterior suitably driven blower 8, whose intake is indicated at 9.

For a purpose to be hereinafter described, the effective discharge area of the air nozzle

7 is made adjustable, as, for example, by the employment of pivoted wings 10, 10 which may be caused to approach each other for the contraction of the nozzle area, or to recede from each other, for the expansion of 55 the nozzle area by any suitable adjusting means, such as the intermeshing gears 11, 11 secured to the pivotal spindles of said wings, and movable angularly in unison by the rocking of an arm 60 12, also secured to one of said spindles. Any other means, well known in the art, may be employed for increasing or decreasing the effective discharge area of the nozzles 7. Also, for a purpose to be hereinafter 65 described, the volume of air supplied to the nozzle 7 by the blower 8 is adjustable or regulable, such adjustment or regulation being secured in any suitable manner as by a pivoted damper 13 disposed in the inlet 9 of 70 said blower and having an operating arm 14.

Beyond its throat 15, the duct 6 provides an extension 16 opening to the atmosphere for the discharge of a portion of the mixed current of air and waste furnace gases,—said 75 gases, as will be well understood, being entrained and drawn upwardly in the duct 6 by the air discharged from nozzle 7. A branch flue or passage 17, communicating with the duct 6 in the vicinity of its throat 80 15, receives that portion of this mixed current of air and waste furnace gases which does not make exit to the atmosphere through the extension 16; a valve or damper 18, disposed at the juncture of branch 17 85 with duct 6 is operable by an arm 19 to establish proportionately the volumes of the mixed current of air and waste furnace gases that pass respectively to the atmosphere (through extension 16) and to the furnace 90 (through branch duct 17). In other words, the position of damper 18 determines the amount of the mixture that is diverted to the furnace for recirculation purposes; if only a small amount is so diverted, then the bulk of said mixture is discharged to the atmosphere through extension 16, while, conversely, if a large amount is diverted through 95 duct 17, then only a small amount is discharged through extension 16.

The duct 17 conveys the mixture flowing therethrough into the fuel intake end of combustion chamber 2, for supporting the combustion of the fuel that is directed 5 through the intake port 3 from any suitable burner 20. As shown in Fig. 1, the duct 17 may communicate by two branches with the combustion chamber 2, one of these branches 21 providing the primary supply 10 of combustion-supporting mixture that enters with the fuel from burner 20 through the intake port 3, and the other branch 22 providing a secondary supply of combustion-supporting mixture that enters by way 15 of a port 23. At the juncture of the two branches 21 and 22 is disposed a valve or damper 24 which is operable by an arm 25 to establish proportionately the volumes of mixture passing, respectively, to the furnace 20 as primary and secondary combustion-supporting supplies,—the position of said damper 24 determining the ratio in which the mixed current is divided between the primary and secondary branches. 25

As shown in Fig. 1, the furnace interior is equipped with a suitable thermostatic device 26, so arranged that variations in temperature within the furnace will produce movements of an arm 27 of said device. The 30 arm 27 may be provided with suitable connections to some or all of the adjustable or regulable elements hereinbefore described; as shown, a cord or cable 28 may run from said arm to the arm 19 of damper 18, and 35 said arm may have its movements communicated in turn to the arm 12 of the adjustable air nozzle 7, as by means of a connecting link 29 between said arms 19 and 12, which link is adjustable in length by means of a 40 turn-buckle or other equivalent device. Also, the movable arm 27 of the thermostatic element 26 may be connected, as by a cord or cable 31, with an operating arm 32 for a 45 throttle valve 33 in the fuel supply line that feeds the burner 20, and another cord or cable 34 may connect said arm 27 with the operating arm 25 of valve or damper 24.

With the apparatus arranged and connected up as described above and as shown 50 in Fig. 1, it is evident that any appreciable increase or decrease of the temperature within the furnace, from the temperature desired and for which the thermostatic device 26 has been set, will influence, in appropriate manner and degree, any one or more of the following factors that have a part in determining the temperature produced in the furnace:—the effective area of the air nozzle 7, the setting of the mixture-diverting damper 55 18, the setting of the mixture-dividing damper 24, and the setting of the fuel supply valve 33. As a result of these automatic adjustments, or any of them, occurring in response to the action of the thermostatic device 26, it is possible to maintain substantially

constant the temperature conditions within the combustion chamber 2, and it will be understood also that such regulation of the furnace temperature may be obtained independently of any device such as 26 which is sensitive to temperature, as by the coordination and tying together, in the manner herein disclosed, of some or all of the adjustable or regulable factors that influence the temperature attained in the furnace. For example, instead of variations in the furnace temperature being made the basis of the coordinated control, as above described, the variations in the amount of fuel admitted to the burner 20 by the throttle valve 33 may be made the basis of the coordinated control; in such a situation, the arm 32 of said valve by suitable connections to the arms 19 and 25 of dampers 18 and 24 respectively would provide by its fuel regulating movements, the necessary movements of said dampers 18 and 24 and of the air nozzle regulating wings 10, 10, such as to increase or decrease the amount of combustion supporting mixture delivered at the ports 3 and 23 in the proper relation to increases or decreases in the amount of fuel supplied, thereby to give the desired furnace temperature.

It will be noted that the air blast from nozzle 7 in the ejector stack or duct 6 performs the function of creating the desired furnace draft, and also performs the function of creating the driving pressure in the throat 15 of stack 6 for the recirculation through the furnace of a predetermined part of the resulting mixture of air and waste gases. These functions are in the main dependent upon the nozzle pressure exerted by the blowing device 8. This nozzle pressure may be varied by varying the resistance or load on the blowing device 8, in response to pressure conditions within the system. To this end, the operating arm 14 of damper 13 in the inlet 9 of said blower, may be connected, as by linkage 35, with a diaphragm 36 of a manometer 37, whose interior chamber is in communication, through a pipe 38, with the offtake passage 5' of the furnace. Variations of pressure in said offtake will therefore be reflected in an increase or a decrease in the amount of air drawn in by the blower 8 and delivered by the nozzle 7.

Fig. 2 depicts a preferred embodiment of the foregoing principles of coordinated regulation and control for furnaces that employ a recirculation of the waste gases. In this embodiment of my invention, the general arrangement of the apparatus is similar to that of Fig. 1, in that the offtake 5, 5' from the furnace chamber 2 is connected to an ejector stack 6, having disposed therein the adjustable air nozzle 7 supplied by a blower 8; also, the same as in the embodiment of Fig. 1, the amount of air admitted to the blower is regu-

lated through manometer 37 by the draft conditions of the system.

The furnace shown in Fig. 2 is equipped with two heat sensitive devices, here shown in the form of thermocouples 39 and 40, of which the first, 39, is so located in the chamber 2 as to be responsive to the flame temperature substantially at the point of initial combustion, while the other, 40, is so located as to be responsive to the lower temperature prevailing at the end or offtake of the furnace chamber. The thermocouple 39 has suitable electrical connections 41 to a control device 42 of conventional type, the latter being associated electrically with a suitable actuator 43 connected to the operating arm 12 for the adjustable wings 10, 10 of the nozzle 7. In this way, the air nozzle-ejector throat ratio and, consequently, the quality or composition of the mixture formed in the throat 15 of ejector stack 6 is regulated by the flame or combustion temperature in the furnace; if such temperature goes too high, the mixture has its proportion of air decreased, and this in turn causes a lowering of the combustion temperature, because the combustion of fuel in the furnace is supported by that part of such mixture which is diverted through the duct or passage 44, corresponding substantially to the duct 17 of Fig. 1. If the combustion temperature goes too low, the mixture is automatically enriched with air, thereby producing a higher combustion temperature in the furnace.

The other thermocouple 40, which measures the end or final temperature in the furnace (after the combustion products have given up part of their heat to the articles or materials that are placed in the furnace to be heated), has suitable electrical connections 45 to a control device 46 of conventional type, the latter being associated electrically with a suitable actuator 47 connected to the operating arm 32 of the throttle valve 33 in fuel supply pipe 33' that feeds the burner 20. Thus when the end temperature within the furnace chamber gets below a predetermined degree, more fuel is admitted through the valve 33, and when this end temperature gets too high, the supply of fuel is correspondingly reduced by said valve. In other words, the amount of fuel supplied to the burner 20 is regulated so as to be substantially proportional to the amount of heat given up by the furnace to the articles and materials that undergo heating in the chamber 2.

Such automatically-produced variations in the flow of fuel to the burner 20 are made to produce corresponding variations in the amount of combustion-supporting mixture diverted to the furnace through the duct or passage 44 from the ejector stack 6, in the following manner:—At a point in the fuel supply pipe 33' before the throttle valve 33 is reached, said pipe provides a plate 48, hav-

ing a restricted aperture 49, and it is obvious that for each change of variation in the rate of fuel flow produced by movement of valve 33, there will be a change of variation in the differential between the pressures prevailing in pipe 33' on opposite sides of said plate 48. The pressure responsive device 50 has the two chambers on opposite sides of its diaphragm 51 connected, respectively, by pipes 52 and 53 with the pipe 33' on opposite sides of said plate. The diaphragm 51 of device 50 is connected, as shown at 54, with an operating arm 55 for the mixture-diverting damper 18 at the juncture of duct 44 with the throat 15 of ejector stack 6. It follows that when the fuel supply to burner 20 is increased, the damper 18 will be automatically moved to a position where more of the mixture from ejector stack 6 is diverted through duct 44, and conversely, when the fuel supply is decreased, the damper 18 will be moved automatically to decrease the amount of diverted mixture, with a corresponding increase in the amount of mixture exhausted to the atmosphere through the extension 16 of ejector stack 6. The mixture diverted to the recirculating duct 44 is preferably conveyed thereby to a heat exchanger or recuperator 56, there to absorb, in its tortuous passage through the same, a portion of the heat contained in the waste gases flowing through the offtake passages 5 and 5' of the furnace,—said exchanger or recuperator 56 providing the conventional tubes 57, 57 for the flow of said waste gases. Thus the diverted combustion-supporting mixture, which ultimately is delivered to the fuel port 3 of the furnace by way of duct or passage 58, undergoes a preheating which results in a more efficient and economical combustion of the fuel supplied by burner 20.

I claim:

1. In a waste gas recirculating system for a heating furnace, an air blast operative for the entrainment and discharge of waste furnace gases, means for diverting a portion of the mixture thus formed of air and furnace gases to the intake of the furnace, to support combustion of the fuel used in said furnace, and means for regulating by the temperature in said furnace the amount of said mixture so diverted.

2. In a waste gas recirculating system for a heating furnace, an air blast operative for the entrainment and discharge of waste furnace gases, means for diverting a portion of the mixture thus formed of air and furnace gases to the intake of the furnace, to support combustion of the fuel used in said furnace, and means responsive to temperature changes within the furnace for varying the ratio between the discharged and the diverted portions of said mixture.

3. In a waste gas recirculating system for a heating furnace, an air blast operative for

- the entrainment and discharge of waste furnace gases, means for diverting a portion of the mixture thus formed of air and furnace gases to the intake of the furnace, to support combustion of the fuel used in said furnace, and means for regulating by the temperature in said furnace the composition of said mixture.
4. In a waste gas recirculating system for a heating furnace, an air blast operative for the entrainment and discharge of waste furnace gases, means for diverting a portion of the mixture thus formed of air and furnace gases to the intake of the furnace, to support combustion of the fuel used in said furnace, and means responsive to temperature changes within the furnace for changing the proportions of the ingredients of said mixture.
5. In a waste gas recirculating system for a heating furnace, an air blast operative for the entrainment and discharge of waste furnace gases, means for diverting a portion of the mixture thus formed of air and furnace gases to the intake of the furnace, to support combustion of the fuel used in said furnace, and means for regulating by the temperature in said furnace the amount of fuel used in said furnace.
6. In a waste gas recirculating system for a heating furnace, an air blast operative for the entrainment and discharge of waste furnace gases, means for diverting a portion of the mixture thus formed of air and furnace gases to the intake of the furnace, to support combustion of the fuel used in said furnace, and means responsive to temperature changes within the furnace for varying the amount of fuel used in said furnace.
7. In a waste gas recirculating system for a heating furnace, an air blast operative for the entrainment and discharge of waste furnace gases, means for diverting a portion of the mixture thus formed of air and furnace gases to the intake of the furnace, to support combustion of the fuel used in said furnace, and means for regulating by the temperature in said furnace the amount of said mixture so diverted and the amount of fuel burned in the furnace with said mixture.
8. In a waste gas recirculating system for a heating furnace, an air blast operative for the entrainment and discharge of waste furnace gases, means for diverting a portion of the mixture thus formed of air and furnace gases to the intake of the furnace, to support combustion of the fuel used in said furnace, and means responsive to temperature changes within the furnace for varying the ratio between the discharged and the diverted portions of said mixture, and for varying the amount of fuel burned in said furnace with the diverted portion of said mixture.
9. In a waste gas recirculating system for a heating furnace, an air blast operative for the entrainment and discharge of waste fur-
- nace gases, means for diverting a portion of the mixture thus formed of air and furnace gases to the intake of the furnace, to support combustion of the fuel used in said furnace, and means for regulating by the temperature in said furnace the composition of said mixture and the amount of fuel burned in said furnace with the diverted portion of said mixture.
10. In a waste gas recirculating system for a heating furnace, an air blast operative for the entrainment and discharge of waste furnace gases, means for diverting a portion of the mixture thus formed of air and furnace gases to the intake of the furnace, to support combustion of the fuel used in said furnace, and means responsive to temperature changes within the furnace for changing the proportions of the ingredients of said mixture and for varying the amount of fuel burned in the furnace with the diverted portion of said mixture.
11. In a waste gas recirculating system for a heating furnace, an air blast operative for the entrainment and discharge of waste furnace gases, means for diverting a portion of the mixture thus formed of air and furnace gases to the intake of the furnace, to support combustion of the fuel used in said furnace, and means for regulating, coordinately, the amount of said mixture so diverted and the amount of fuel burned in said furnace.
12. In a waste gas recirculating system for a heating furnace, an air blast operative for the entrainment and discharge of waste furnace gases, means for diverting a portion of the mixture thus formed of air and furnace gases to the intake of the furnace, to support combustion of the fuel used in said furnace, and means for regulating, coordinately, the composition of said mixture and the amount of fuel burned in said furnace.
13. In a waste gas recirculating system for a heating furnace, an air blast operative for the entrainment and discharge of waste furnace gases, means for diverting a portion of the mixture thus formed of air and furnace gases to the intake of the furnace, to support combustion of the fuel used in said furnace, and means for regulating, coordinately, the composition of said mixture, the amount of the same so diverted, and the amount of fuel burned in said furnace.
14. In a waste gas recirculating system for a heating furnace, an air blast operative for the entrainment and discharge of waste furnace gases, means for diverting a portion of the mixture thus formed of air and furnace gases to the intake of the furnace, to support combustion of the fuel used in said furnace, and means for regulating by the combustion or flame temperature in said furnace the composition of said mixture.
15. In a waste gas recirculating system for a heating furnace, an air blast operative

- for the entrainment and discharge of waste furnace gases, means for diverting a portion of the mixture thus formed of air and furnace gases to the intake of the furnace, to support combustion of the fuel used in said furnace, and means for regulating by the end temperature in said furnace the amount of fuel used in said furnace.
16. In a waste gas recirculating system for a heating furnace, an air blast operative for the entrainment and discharge of waste furnace gases, means for diverting a portion of the mixture thus formed of air and furnace gases to the intake of the furnace, to support combustion of the fuel used in said furnace, means for regulating by the combustion or flame temperature in said furnace the composition of said mixture, and means for regulating by the end temperature in said furnace the amount of fuel used in said furnace.
17. In a waste gas recirculating system for a heating furnace, an air blast operative for the entrainment and discharge of waste furnace gases, means for diverting a portion of the mixture thus formed of air and furnace gases to the intake of the furnace, to support combustion of the fuel used in said furnace, and means for regulating by the end temperature of said furnace the amount of fuel used therein and the amount of said mixture so diverted.
18. In a waste gas recirculating system for a heating furnace, an air blast operative for the entrainment and discharge of waste furnace gases, means for diverting a portion of the mixture thus formed of air and furnace gases to the intake of the furnace, to support combustion of the fuel used in said furnace, means for regulating by the combustion or flame temperature in said furnace the composition of said mixture, and means for regulating by the end temperature in said furnace the amount of fuel used in said furnace and the amount of said mixture so diverted.
19. In the operation of a heating furnace, the improvement which consists in entraining the waste furnace gases by a blast of air on the outgoing side of the furnace, diverting a portion of the resulting mixture of air and waste gases to the ingoing side of the furnace to support combustion therein, and regulating, coordinately, the amount of mixture so diverted and the amount of fuel used in said furnace.
20. In the operation of a heating furnace, the improvement which consists in entraining the waste furnace gases by a blast of air on the outgoing side of the furnace, diverting a portion of the resulting mixture of air and waste gases to the ingoing side of the furnace to support combustion therein, and regulating, coordinately, the composition of said
- mixture and the amount of fuel used in said furnace.
21. In the operation of a heating furnace, the improvement which consists in entraining the waste furnace gases by a blast of air on the outgoing side of the furnace, diverting a portion of the resulting mixture of air and waste gases to the ingoing side of the furnace to support combustion therein, and regulating, coordinately, the composition of said mixture, the amount of the same so diverted, and the amount of fuel used in said furnace.
22. In the operation of a heating furnace, the improvement which consists in entraining the waste furnace gases by a blast of air on the outgoing side of the furnace, diverting a portion of the resulting mixture of air and waste gases to the ingoing side of the furnace to support combustion therein, and regulating by the temperature in said furnace the amount and composition of the mixture so diverted and the amount of fuel burned in said furnace.
